(57) **CLAIM**

The ornamental design for a lavatory, as shown and described.

DESCRIPTION

In a preferred embodiment, the nature of this product is a lavatory for washing various items and human body parts.

FIG. 1 is a top, left, front perspective view of a lavatory embodying my new design;

FIG. 2 is a top plan view thereof;

FIG. 3 is a front elevational view thereof;

FIG. 4 is a left side elevational view thereof, the right side elevational view thereof being a mirror image of the left side shown;

FIG. 5 is a rear elevational view thereof;

FIG. 6 is a bottom plan view thereof;

FIG. 7 is a sectional view take along line 7—7 of FIG. 2;

FIG. 8 is a top, left, front perspective view of a lavatory according to another embodiment of my new design;

FIG. 9 is a top plan view thereof;

FIG. 10 is a front elevational view thereof;

FIG. 11 is a left side elevational view thereof, the right side elevational view thereof being a mirror image of the left side shown;

FIG. 12 is a rear elevational view thereof;

FIG. 13 is a bottom plan view thereof; and,

FIG. 14 is a sectional view taken along line 14—14 of FIG. 9.

The broken line representations in the figures are for the purpose of illustration only, and form no part of the claimed design.
